UNITED STATES PATENT OFFICE.

ALBERT L. GRAYSON, OF RUTHERFORDTON, NORTH CAROLINA.

GATE-LATCH.

SPECIFICATION forming part of Letters Patent No. 241,646, dated May 17, 1881.

Application filed March 16, 1881. (Model.)

To all whom it may concern:

Be it known that I, ALBERT L. GRAYSON, of Rutherfordton, Rutherford county, North Carolina, have invented a new and Improved 5 Latch for Gates, of which the following is a specification.

The object of my invention is the production of a latch for gates which shall be efficient, cheap, durable, and simple of construction, and 10 one which will not be effected by the shrinking and swelling of the gate or by the ordinary lateral bearing or displacement of the gate-posts.

My invention consists of a wire or rod of iron 15 bent into a square loop, one end of the rod being extended to pass through the gate and have a knob or other means of turning or swinging the loop for unlocking the gate secured to it, the loop being adapted to catch over a triangular projection or keeper secured to the gate-post.

In the accompanying drawings, Figure 1 is a front elevation of a gate having my invention attached. Figs. 2 and 3 are respectively 25 side and front views of my invention, and Fig. 4 is a top view of the same.

Similar letters of reference indicate corresponding parts.

A represents the latch, and B the keeper. 30 The latch A is formed preferably of the round rod *a*, of iron, bent as shown, to form the square loop D, the end *a'* of the rod being extended, as shown, and adapted to pass through the upright bar H, in which it is loosely held, and 35 to have knob C secured to its outer end, for turning the latch for opening the gate. The keeper B is preferably triangular in form, and

may be of wood or metal. It is secured to the gate-post E by means of the screws *b b*, in such position relative to the position of the 40 latch on the gate that when the gate is closed the loop will ride up the inclined face of the keeper and drop or fall over the square face thereof, and thus retain the gate closed.

In order to open the gate, the knob should 45 be turned so as to raise the lower part of the loop out of contact with the front face of the keeper, and thus disengage it therefrom, leaving the gate free to be opened.

To prevent the loop being caught between 50 the gate and the gate-post E while the gate is being closed, I provide the gate with the pins *c c*, near the top and lower side of the loop and on opposite sides thereof, which prevent the swinging of the loop, except in the proper direction.

Instead of making the keeper of wood and securing it to the post by screws, as shown, the catch may be formed of sheet metal or of a rod of iron, and not depart from the spirit 60 of my invention.

Having thus described my invention, I claim as new and desire to secure by Letters Patent—

The latch D, formed of a rod of iron bent so 65 as to form a square loop, and having the extension *a'*, in combination with the knob C, pins *c c*, and the keeper B, substantially as shown and described.

ALBERT LOGAN GRAYSON.
